PUPPET

Franklin Burr Tillstrom, Chicago, Ill.

Application September 21, 1950, Serial No. 12,279

Term of patent 14 years

(Cl. D34—2)

To all whom it may concern:

Be it known that I, Franklin Burr Tillstrom, a citizen of the United States, residing in the city of Chicago, county of Cook, State of Illinois, have invented a new, original, and ornamental Design for Puppets, of which the following is a specification, reference being had to the accompanying drawing, forming part thereof, and in which

Figure 1 is a perspective view of a puppet with the mouth in open position, showing my new design;

I claim:

The ornamental design for a puppet, as shown.

F. BURR TILLSTROM.
